UNITED STATES PATENT OFFICE.

JOSEPH E. VOREL, OF MILWAUKEE, WISCONSIN.

APPARATUS FOR TREATING HIDES.

1,254,179.

Specification of Letters Patent. Patented Jan. 22, 1918.

Application filed March 6, 1917. Serial No. 152,539.

To all whom it may concern:

Be it known that I, JOSEPH E. VOREL, a citizen of the United States, and resident of Milwaukee, in the county of Milwaukee and State of Wisconsin, have invented certain new and useful Improvements in Apparatus for Treating Hides; and I do hereby declare that the following is a full, clear, and exact description thereof.

10 My invention relates to new and useful improvements in treating hides and skins of various kinds, it being the object of the invention to greatly improve the present methods of tanning, dyeing and otherwise treating raw materials of this character.

15 With the systems now in use only a very small number of hides or skins can be treated at one time and in one receptacle, therefore it is necessary to build a large number of 20 these receptacles in order to tan skins in large quantities.

25 These ordinary receptacles in which the skins are at present treated, not only take up a considerable amount of space in the tannery, but it has also been found that the skins from one receptacle will be considerably different in texture or coloring from those treated in other receptacles.

30 My present invention has been designed with the idea of overcoming these difficulties, and by the use of the apparatus to be hereinafter described, many thousands of skins may be treated in one tank. In order to give each skin the same treatment 35 afforded all of the others, a novel means is provided for thoroughly agitating the liquid in the tank.

30 The invention resides in the novel features of construction, combination and arrangement of parts which will be herein- 40 after more particularly described and claimed and shown in the accompanying drawing, wherein:

45 Figure 1 is a plan view of the apparatus. Fig. 2 is a central vertical longitudinal section on the line 2--2 of Fig. 1.

50 Referring to the several figures of the drawing in detail, it will be noted that the numeral 1 designates the outer wall of a tank of substantially oval shape in plan view, 2 being an elongated substantially oval filling member having semi-circular ends 3 which is disposed longitudinally and centrally of the tank as clearly shown in

Fig. 1. This arrangement forms a substantially oval shaped endless channel 4 adapted to contain a suitable liquid for treating hides and skins which are to be placed therein.

55 The wall 1 and the member 2 as well as the floor or bottom of the tank are preferably formed of concrete. The tank may be built in any desired shape and in any preferred size, but it has been found that an oval shaped tank, such as illustrated in the drawing will operate to the best advantage. The depth and length of the channel 4 depends entirely upon the number of skins or hides which are to be treated and the size of the plant in which the apparatus is to be 60 installed. In order for the apparatus to properly operate, however, it is essential that the parts of the channel in each side of the filler member be substantially straight and of a length approximately 65 equal to or greater than twice the width of the tank. If these sides are of less length the hides and skins will not travel through the end portions of the channel because they will not acquire sufficient momentum from 70 the agitating means to be later described. This will obviously cause clogging of the channel at the ends thereof.

75 One end of the tank is provided with an inlet opening 5 while the other end has an outlet opening 6, each being formed through the wall 1 adjacent its connection with the bottom 7. Each of the openings 5 and 6 contains a casing from which projects outwardly a hollow nipple 8, the same having 80 a plurality of apertures 9 formed in its wall, while a threaded stud 10 projects from its end. A head 11 is disposed to rotate on each of the nipples 8 and has an annular 85 passageway adapted to surround the apertures 9, said passageway in the head communicating with an inlet or an outlet pipe as the case may be. The inlet pipe is designated by the numeral 12 and the outlet pipe, 90 which is in the form of a short pipe section, bears the numeral 13. After the heads have been placed upon their nipples and nuts 14 threaded on the studs 10, the same 95 will be held in operative position thereon, they being designed to rotate to position 100 the pipes 12 and 13 at any angle with respect to the horizontal.

105 As a result of this construction, a continu-

ous flow of liquid may be maintained through the tank, and the height thereof retained at any desired level. Or the liquid may be allowed to remain within the tank 5 without any additional supply of fresh liquid for any required length of time. It is obvious that by disposing the pipe section 13 at any angle to the horizontal, and retaining it in this position the height of the 10 liquid in the tank may be readily regulated. For instance, if the liquid is to be raised nearly to the top of the tank, the pipe section 13 is disposed substantially vertical with its open end upward, but if the liquid 15 is to be drained off, said pipe section is placed as shown in Fig. 2.

As heretofore mentioned, the tank may be utilized for treating the hides and skins in any one of the various methods common 20 to those skilled in the art for the purpose of tanning the same, and it may also be used for dyeing or otherwise coloring the hides and skins before or after they have been otherwise treated. In the latter case the 25 coloring matter may be added to the liquid contained in the tank from either one or both of the small mixing chambers 15, one of which is formed in each end of the member 2 and has a valve 16 to regulate the 30 quantity of liquid flowing therefrom. These chambers may be used to mix the coloring matter before it is applied to the liquid in which the hides are to be placed, and in this manner it is more evenly distributed. 35 The agitating means which will presently be described further serves to thoroughly mix the coloring matter with the liquid in the tank. These chambers 15 may be used for storing any other kinds of material 40 which is to be added to the tank in small quantities.

The above mentioned agitating means in the present instance consists of a pair of revolving paddle wheels 17, one of which is 45 disposed on each side of the member 2 adjacent the ends thereof and has its blades disposed in the channel 4 thus disposing the wheels on opposite sides of a vertical plane passing transversely through the center of the tank. This disposition of the wheels causes them to act upon the fluid and the skins immediately after the same has passed around the curved ends of the channel and also permits said fluid to have 55 a relatively long sweep through the straight portions of said channel to prevent clogging of the skins at the ends of the tank. Although but two paddle wheels have been illustrated it is obvious that more or less of 60 them may be used, depending upon the size of the tank and the length of the channel thereof. Each paddle wheel is preferably similarly constructed, and, as shown in the drawing, consists of a shaft 18 journaled in 65 bearings 19 carried respectively by the wall

1 and member 2, and a plurality of radially extending arms 20 which carry blades 21.

The outer end of each shaft 18 has a sprocket or other form of gear wheel 22 fixed thereto, and adapted to have a sprocket chain or other connection 23 trained therearound, said chains connecting the wheels 22 with similar wheels 24 mounted on the opposite end of each of a pair of parallel 75 shafts 25. The latter shafts are journaled in the upper ends of standards 26 carried by the wall 1. These shafts 25 are connected together by a pair of pinions 27, and one of them has a pulley 28 fixed thereto, to 80 which power from a suitable source may be applied by a belt 29. It will be seen that when the pulley 28 is rotated, the paddle wheels 17 will be rotated in opposite directions so that the liquid contained in the 85 tank will continuously flow in one direction therethrough as long as the wheels continue to revolve. The skins contained in the liquid will always be moved therewith unless they are secured to the sides of the tank. 90

After the hides or skins have been sufficiently treated they are ready to be removed from the tank and in order to facilitate their removal a gate 30 has been provided against which they will contact as 95 they are moved through the channel by the paddle wheels. The gate 30 is slotted to permit the liquid to pass therethrough and to prevent the hides or skins from passing therebeyond. In this manner all of the 100 skins or hides may be collected at one end of the tank and removed therefrom onto a suitable slotted platform 31 and carried to a place of storage or wherever needed.

It will be obvious from the foregoing description, that an exceedingly simple apparatus for washing, dyeing, pickling, and unhairing or otherwise treating skins and 105 hides of various kinds has been produced. Furthermore it will be noted that the treatment may be carried through with less time than with the ordinary small tanks which are now commonly in use, and that the skins 110 will be of much better quality than those now produced.

I claim:

An apparatus of the class described, comprising a stationary liquid containing tank having its ends rounded, the length of said tank on each side of its center being greater 120 than its width, a longitudinally extending centrally disposed filler member positioned in the tank to form an endless channel, the portion of the same on each side of said filler member being approximately straight, 125 each approximately straight portion of the channel being of a length substantially twice the width of the tank, and means for causing a continuous flow of fluid in one direction through said channel, said means in- 130

cluding a revoluble agitating member disposed in each straight portion of the channel, said agitating members being adjacent the opposite ends of the filler member and 5 on opposite sides of a vertical plane passing transversely through the center of the tank, whereby to actuate the fluid immediately after having passed around the curved ends of the channel and to give the same a rela-

tively long sweep through the straight portions of said channel, and means for rotating said agitating members.

In testimony that I claim the foregoing I have hereunto set my hand at Milwaukee, in the county of Milwaukee and State of Wisconsin.

JOSEPH E. VOREL.
